United States Patent Office

Des. 183,622

Patented Sept. 30, 1958

183,622

COMBINED CLOSURE AND DISPENSING CAP

Sidney M. Libit, Glencoe, Ill.

Application September 9, 1957, Serial No. 47,661

Term of patent 14 years

(Cl. D58—26)

Fig. 1.

Fig. 2.

Fig. 3.

Fig. 1 is a front elevational view of a combined closure and dispensing cap showing my new design;

Fig. 2 is a front elevational view thereof, shown partly in section, and

Fig. 3 is a top plan view thereof.

I claim:

The ornamental design for a combined closure and dispensing cap, substantially as shown.
